Primary Examiner — Martie K Holtje(74) *Attorney, Agent, or Firm* — Finnegan, Henderson, Farabow, Garrett & Dunner, L.L.P.(57) **CLAIM**

The ornamental design for a airship, as shown and described.

DESCRIPTION

FIG. 1 is a front perspective view of a airship showing our new design;
FIG. 2 is a front elevation view thereof;

FIG. 3 is a right side view thereof, the left side view being a mirror image thereof;

FIG. 4 is a rear view thereof;

FIG. 5 is a top plan view thereof; and,

FIG. 6 is a bottom view thereof.

The structural features depicted by broken lines have been shown for the purpose of illustrating portions of the airship that form no part of the claimed design.
